(54) **SHINGLES, SHAVING & JOINTING**

(76) Inventor: **Samuel B. Chapman**

Samuel B. Chapman, Camden, New Jersey.
Sitter's Patent.

Dated March 15th 1834. Received June 12th 1835.

The Schedule, referred to in this Sitter's Patent and making part of the same, containing a description in the words of the said Sam'l B. Chapman himself of his improvement in shoring and pointing shingles, Patented to him on the fifteenth day of March 1834, which Patent being hereby cancelled on account of an incorrect specification.

To all whom it may concern: Be it known that Sam'l B. Chapman of Camden in the County of Gloucester, and State of New Jersey, have invented an improvement in a new and useful machine for shoring and pointing shingles of which a full and perfect and distinct specification or description was given, and attached to Sitter's Patent of the United States, granted to me on the fifteenth day of March 1834, and I do hereby declare that the following is such a full and exact description thereof as I believe fulfills the requirements of the law in all respects, which the former, through inadvertence and want of proper information failed to do: A strong bench is to be made by framing suitable timber together to form the sides, ends, legs and cross pieces. Its size may vary to suit the place it is intended for. In ordinary cases it may be about nine feet long, three feet wide and two feet high. Upon one end of the bench I place a frame usually of cast iron which is to contain a pair of rollers between which the shingle are to pass in their way to the knives, behind them the knives, and behind them another pair of rollers to carry the shingle as it leaves the knives. The frame is quadrangular, and an iron post or standard rises at each of its corners. The two front posts contain the two front rollers. The lowermost of which is so fixed that its upper side rises a little above the plane or top form of the bench; this roller serves to conduct the shingle against the lower knife. The upper roller stands immediately over the former, its guides are so arranged in a sliding frame, which allows it to rise and fall, being guided by grooves in the post or standards, the frame is sprung down by a strong box spring, or by spiral, or other springs, as may be preferred, the object being to keep the roller in constant contact with the shingle instead of this upper front roller, sometimes from the sliding frame with its lower surface flat, and allow this to descend upon the shingle in the way described when the staff is twisted, or uneven; this I think may be preferred to the roller. There are two rollers at the back of the frame carrying

it from one standard to the other in the same plane with the front rollers, the upper roller being borne down exactly in line, as described, they serve to receive the shingle as it is being shaved, and to keep it in its place relative to the knives. The iron frame, containing the rollers and other parts, may be about two feet long, measuring across the platform, and about one foot deep from front to back. The knives stand across the platform, the lower one being fixed thereto, is stationary, its edge of course being so fixed as to take a shaving from the lower side of the shingle, as it passes from roller to roller. The upper knife is placed exactly above the lower, and is capable of approaching or receding from it for the purpose of regulating the varying thickness of the shingle, it being made to approach, as the shingle passes through, in a way to be presently described. The knives may be about four inches wide, and one and a half inches thick, and for the purpose of applying the gauges which regulate their distance apart, they are made sufficiently long to project at each end beyond the iron frame. The upper knife is borne upon iron blocks which by means of levers and screws, slide up and down between thin posts or standards, at each end of the frame, an iron sliding gauge passes between the ends of the knives in a way to be presently described, and serves to keep them at the intended distance apart. From each of the iron blocks which bear upon the upper knife, vertical rods rise, and they are connected together at the upper ends by a horizontal cross bar. An eccentric may be made to operate upon this cross bar, simultaneously with the passage of the shingle between the knives, so as to force the upper knife down as the shingle advances, and to permit when another is to be passed through otherwise, the knife to rise, may be rotated, to force the knife down as will appear hereafter. Along the middle of the table there is a groove, which serves as a guide to the driver or pitman, which is to force the shingle forward. The driver is a piece of hard plank six or eight inches wide, which being forced on by the action of a crank, upon a rod, or bar, to one end of which it is attached, causes the unshaved shingle, which is laid upon the platform, to be forced in between the rollers and knives, and thus in its turn is forced out by the next following shingle. This driver, makes in fact a part of a sliding frame which lies upon the bench. Another part of this sliding frame, consisting of two iron rods which extend back, and constitute the gauge between the knives. A cross bar, and by its middle to the rod to which the driver is attached, has a iron bar or rod fastened to each of its ends, so as to be upon the frame of the bench, and to extend back between

the knives, which other rods are tapered as the shingle is in thickness after it is dressed. These quay rods, being driven on at the same time with the shingle determine its thickness, the upper knife being forced down upon it by the lower block, and eccentric, which eccentric may be fixed to a shaft, and receive its motion from the same power which drives the crank shaft. Instead of using the eccentric in the way described, the quay rods may each be made double, when they operate upon the upper knife, one part passing above, and the other below, the end of the movable knife. These two parts may then be tapered equally, and in opposite directions, and the upper rod must then and slide against a fixed block or obstacle. The same principle may be applied if desired, to cause the knives each to advance towards the other which will undoubtedly have the shingle more smoothly than when half only advances. The jointing is effected by means of points which lie upon the platform, in front of the saw frame, one on each side of the shingle. They have each three or four rows, are confined so as to slide towards each other, and are bound together by springs, these do not differ materially from such as have before been used, and do not need therefore to be particularly described, but the drawing deposited in the Patent Office will show their construction and that of the other parts of the apparatus. Scamions perform the jointing and shingling distinct operations, as shorter ranks answer the purpose than that necessary to effect both at once. The same crank shaft may in this case have two cranks upon it, the beech being widened but for this purpose.

What I claim as my invention is the manner of fixing the knives within the iron frame and the giving to one or both of them a vertical motion only, for the purpose and in the manner, or upon the principle herein set forth. I also claim the use of rollers or segments of rollers, to receive the pressure upon the shingle after it has passed in part through the knives.

John Atkinson, Same 13 Chapman av.

Edward Harris
